UNITED STATES PATENT OFFICE

96,320

DESIGN FOR A SHOE

Eugene Lampel, Brooklyn, N. Y.

Application March 8, 1935, Serial No. 55,786

Term of patent 3½ years

To all whom it may concern:

Be it known that I, Eugene Lampel, a citizen of the United States and resident of New York city, in the county of Kings and State of New York, have invented a new, original, and ornamental Design for a Shoe, of which the following is a specification, reference being had to the accompanying drawing, forming part thereof, in which

Fig. 1 is a plan view of the shoe, showing my new design; and

Fig. 2 is a side elevational view of the shoe shown in Fig. 1.

A dominant feature of the design resides in the appearance obtained by rows of parallel slits and intervening lips showing the underside of the leather thus producing a two-tone effect, the rows of slits being so arranged as to give a herringbone effect.

I claim:

The ornamental design for a shoe as shown and described.

Dated, December 24, 1934.

EUGENE LAMPEL.
